UNITED STATES PATENT OFFICE.

SADIE L. JOHNSTON, OF NEW YORK, N. Y.

CIGARETTE-CASE.

1,236,442.

Specification of Letters Patent. Patented Aug. 14, 1917.

Application filed March 13, 1917. Serial No. 154,432.

To all whom it may concern:

Be it known that SADIE L. JOHNSTON, a citizen of the United States, residing at New York, in the county of New York and State of New York, has invented certain new and useful Improvements in Cigarette-Cases, of which the following is a specification.

My present invention relates to improvements in containers, and more particularly to containers for articles which are to be carried in the pocket. While the container may be used in connection with various articles, it is designed more particularly as a carrier for cigarettes, thus forming what may be termed a cigarette case, although it is to be understood that this title is not intended to limit the invention to such particular use.

Various forms of cases for this purpose have heretofore been provided, being designed more particularly to meet conditions which are inherent in the article. For instance, the cigarette must be free from damage in order to provide satisfactory smoking, and hence a carrier therefor, must eliminate, as far as practicable, the possibility of damaging the cigarette while the case is being carried in the pocket. To meet this condition the containers have generally been arranged to carry the cigarettes in a longitudinal row or a plurality of rows with means for retaining the cigarettes in position against damaging action. This result has generally been obtained structurally, where the cigarettes have paper wrappers, by providing a receptacle for the cigarettes, and mounting the receptacle within a casing—generally of leaf form—the receptacle generally being connected to the casing, so that when the latter is open the receptacle will be so exposed as to permit of ready removal of individual cigarettes. Such structures are necessarily somewhat expensive to manufacture owing to the form of the mechanical construction employed. In addition, they are necessarily of considerable depth, thus tending more or less to bulkiness of the container.

The present invention is designed more particularly to produce an efficient carrier of decreased cost in manufacture, which is comparatively thin or of shallow depth,

thereby materially decreasing the bulkiness of the container, and at the same time provide a structure which will maintain the integrity of the cigarettes regardless of the character of handling of the case. 55

The invention also meets an additional condition primarily brought about by the formation of the cigarette itself. The tobacco contained in the cigarette is of comparatively short length. Consequently, a considerable amount of tobacco at the ends of the cigarette can be sifted out by shifting or moving the cigarette about in a case or subjecting such cigarette end to material pressure. It has been found that where some of the cigarettes of a row have been removed and the remainder permitted to shift position, cigarette movements of sufficient magnitude may be provided while the case is being carried in the pocket, with the result that the tobacco will sift from the ends of the cigarettes. As one of the essentials in maintaining the integrity of a cigarette is that no material external pressure should be placed on the cigarette such as is provided by a clamp or finger adapted to clamp the cigarettes in the case it will be understood that prevention of cigarette shifting by frictionally holding the cigarette is inadvisable. This shifting can be prevented, of course, by providing individual pocket configurations for the cigarettes carried by a supplemental holder member inclosed between the case sections, but, this in turn, tends to increase the cost of manufacture and also of bulkiness in the type of structures heretofore employed. 75 80 85 90

To these and other ends, the nature of which will be readily understood as the invention is hereinafter disclosed, said invention consists in the improved construction and combination of parts hereinafter fully described, illustrated in the accompanying drawings, and more particularly pointed out in the appended claims. 95

In the accompanying drawings, in which similar reference characters indicate similar parts in each of the views:—

Figure 1 is a perspective view showing a case embodying the principles of the present invention, the case being shown as closed.

Fig. 2 is a perspective view showing the

case as open, the interior of the case being arranged in accordance with one embodiment of the invention.

Fig. 3 is a perspective view of the opened case of Fig. 2, showing the manner in which the cigarettes are individually removed from the case.

Fig. 4 is a detail cross-sectional view taken on line 4-4 of Fig. 5.

Fig. 5 is a sectional view taken on line 5-5 of Fig. 4.

Fig. 6 is a perspective view of a different embodiment of the invention, the case being shown as open, the cigarettes being omitted.

Fig. 7 is a sectional view of the structure of Fig. 6.

As shown in the drawings, decrease in cost of manufacture and decrease in thickness of the case is provided to a more or less extent by eliminating the internal receptacle and the mechanical structures by which such receptacle is mounted within the case. This is obtained by giving at least one of the case walls a configuration which will not only act as a receptacle element, but which will also retain the individual positioning of the cigarettes so that each cigarette will remain in position until actually removed from the case. This arrangement necessarily changes the manner of manipulating the cigarettes to remove them from the case since the cigarettes necessarily have their ends depressed with respect to the section edge or edges and, therefore, only partially exposed above the plane of such edge, whereas the independent receptacle type provides an entire exposure of such end. While removal of cigarettes from a depressed position can be obtained by lateral movement, such movement is not desirable, since any attempt to raise a cigarette at its ends is difficult, due to the restricted space between the cigarette end and the casing, so that liability of damage to the cigarette end is present; to grasp the cigarette at an intermediate portion tends to provide pressure thereon and thus affects the cigarette. In addition exposure of the entire row of cigarettes to permit of such lateral movement tends to disarrange the row since it is difficult to manipulate one cigarette without affecting others.

For these reasons it is generally desirable to remove the cigarette by an endwise movement. This is, of course, readily possible where the ends of the cigarettes are completely exposed in the case as in the independent receptacle type. However, where the cigarette ends are but partially exposed, the problem is complicated through the requirement that the cigarette must be moved to a position to completely expose the end before removing the cigarette, and at the same time prevent the application of pressure on an intermediate portion of the cigarette. In addition it is essential to re-

tain the positions of the cigarettes which are not being removed in order that liability of damage to the cigarette be decreased as far as possible. These conditions are met in the case structures now to be described.

Referring more particularly to Figs. 1 to 5 inclusive, 10 and 11 indicate two leaf sections hingedly connected along their longer or side edges. Each section is shown as dished to provide case edges, adapted to be brought into contact when the case is closed, and a space within the case.

In the drawings, each section is shown as corrugated or provided with parallel depressions 12. However, this particular corrugated configuration of section 10 may be omitted, if desired, without avoiding the principles of the present invention, the corrugated form of the section causing the case to have a more symmetrical appearance externally.

As shown, the depressions preferably have a length greater than the length of the cigarettes which are to be positioned therein and at least the outer end of each depression is decreased in depth toward the adjacent section edge. In the forms shown this is had by curving the body of the section in the direction of length of the depression so as to cause the end of the cigarette to freely ride up to and over the section edge when the cigarette is advanced in such direction by a pushing action at the opposite end of the cigarette as shown in Fig. 3.

Each end of the depression may be, and preferably is, formed with such decreased depth. As this decreased depth configuration preferably extends a distance sufficient to carry it below the end of the cigarette, the similar formation of the opposite ends of the depression will tend to produce a slight bridging action on the cigarette. This arrangement, does not affect the cigarette as long as no material pressure is placed on the body of the cigarette, and it may be more or less advantageous in permitting the use of a cigarette-retaining device which may be brought into closer contact with the body of the cigarette, since the change in angularity of the cigarette during its advancing movement and while riding over such curved portion is more or less compensated by reason of the fact that the opposite end is moved into a portion of the depression of increased depth, so that such change in angularity does not affect or damage the cigarette. However, this complete bridging effect may be omitted and the decrease in depth formation be located entirely at the outer end of the depression, the retaining device then being of a looser fit to permit advancing movement of the cigarette without damaging the latter.

In these figures of the drawing, the retaining device is in the form of a band 13

of suitable width and secured to the ends of section 11 in suitable manner, as, for instance, by soldering, the band extending transversely of the direction of length of the depressions and being preferably corrugated in opposition to the corrugated formation of the section. The band is adapted to overlie the cigarettes, coöperating with the depressions to form complete pocket-like configurations through which the cigarettes extend.

As shown, the band is positioned intermediate of and spaced from the ends of the depressions—intermediate the ends of the cigarettes—and is preferably so located as to permit a sufficient length of cigarette advancing movement to carry the advance end of the cigarette beyond the section edge while the opposite end of the cigarette is being pushed forward, the arrangement being such that each of the cigarettes is exposed to permit this action to be obtained. The band is also preferably located closer to the inner end of the cigarette in order that the change in inclination of the cigarette during its advance movement will not place a material pressure on the body of the cigarette.

When the case is closed, band 13 is practically nested within the depressions of section 10 and the arrangement is such that substantially no pressure is placed on the cigarettes by section 10. Obviously, the absence of the corrugations in section 10 will not affect this result as long as the dished form of the section is such as to permit the band to be received therein without applying pressure on the cigarettes when the case is closed.

The number of depressions in section 11 will, of course, depend upon the maximum number of cigarettes which are to be positioned in the case, the construction being preferably intended to provide a single row of cigarettes, thus producing a case which is thin and flat and which can be readily carried in the pocket.

This arrangement practically forms an individual pocket for each cigarette and within which it will remain without material shifting even though other cigarettes are removed. Hence, liability of tobacco sifting is reduced to a minimum. In addition, the provision of depressions which are more or less curved cross-sectionally and which have the curved depression ends serves to produce a structure of a type which is especially adapted to resist inward pressure on the walls of the case, a structure of material advantage in that the thickness of the casing metal may be reduced and thus decrease the cost of manufacture. This is especially true by reason of the fact that the intermediate portions of the cigarettes are normally out of contact with the walls of

the case, and, therefore, more or less free from liability to damage through pressure applied when the case is closed.

As will be understood, the permanently-positioned band structure of Figs. 2 and 3 practically requires that the cigarettes be introduced individually, each cigarette being introduced into its depression and then moved to position or permitted to move to such position.

In Figs. 6 and 7, I have shown a modified arrangement where the cigarettes may be introduced collectively and distributed over the depressions. This result is obtained by mounting the band in such manner as to be movable from its normal position. This result can be obtained in various ways. In these views the band is shown as mounted on a pair of arms 14 which form extensions of the hinge pintle to move therewith or to be practically free from movement with section 10, while permitting relative movement between section 11 and the pintle when pressure is placed on arms 14 to shift the latter from normal position the application of such pressure permitting movement of the band to the position shown in Fig. 7, thus exposing the depressions of section 11 throughout their length. When so positioned, the cigarettes can be placed on the section collectively, spread thereover so as to locate the cigarettes in the several depressions, and the band then pushed back to its normal position, the arrangement being such that arms 14 will prevent inward movement of the band beyond such normal position and thus avoid placing pressure on the cigarettes.

Obviously, this arrangement of a support for the band is but one of a number of forms in which this support may be provided, any of which may be employed for the purpose. One of the essential features of such mounting, however, is that the support should not obstruct the inner ends of either of the depressions to an extent sufficient to prevent free access of the thumb or finger to give the cigarette the desired advance movement. While such movable band structure is made possible, it is preferred that no movement of the band take place excepting during the filling operation, it being preferred to provide for the individual removal stick as is contemplated by the fixedly positioned band.

In each form, however, the band is supported at its ends to substantially maintain its cigarette-retaining position; the means for supporting the band may be the solder formation or a movable support, as indicated.

As is usual in cases of this type, I prefer to provide for automatic opening of the case when the clasp is released, various forms of such structures being well-known and applicable for use. For instance, the usual torsional spring structure may be employed

130

in connection with the case of Figs. 2 and 3, but, where the specific form of mounting shown in Fig. 6 is employed, I prefer to employ the usual coil spring arrangement, 5 since the pindle is being more or less frictionally held. Obviously, this latter structure may be employed with the form of Fig. 2.

The clasp, indicated at 15, is of a general 10 type, preferably spring supported, and for the purpose of producing a symmetrical appearance, is preferably shaped to fit the outer configuration of the section over which it closes.

15 While I have shown the hinge line as extending along the longer side of the sections and transverse to the direction of length of the depressions, it will be readily understood that the sections can be hinged along their 20 ends, thus placing the hinge line parallel to the direction of length of the depressions.

The case may be formed of any desired material, as metal, paper or card board, etc.

While I have herein shown various ways 25 in which the principles of my invention may be carried out, it will be understood that changes and modifications therein may be required or desired to meet the various exigencies of use, and I desire to be understood 30 as reserving the right to make any and all such changes or modifications in so far as the same may fall within the spirit and scope of the invention as expressed in the accompanying claims:

35 Having thus described my invention, what I claim as new, is:—

1. A cigarette case comprising a pair of hingedly connected leaf sections oppositely dished to inclose the cigarettes when the sections are closed, at least one of said sections being corrugated to form depressions of a length greater than the length of the cigarettes and within which the cigarettes are seated individually, and a band extending 40 transversely of the direction of length of the depressions intermediate of and spaced from the depression ends, said band being corrugated oppositely to said depressions and coöperating therewith to complete 45

50 pocket-like configurations through which the cigarettes extend, said band normally maintaining the cigarettes seated in such depressions while permitting endwise movement of a cigarette in the direction of length 55 of its depression at will, the position of the band permitting such movement for a distance sufficient to project the opposite end of the cigarette beyond the section edge.

2. In a cigarette case, a dished leaf section 60 having parallel depressions of a length greater than that of the cigarettes and with the advance end of each depression decreasing in depth toward the adjacent edge of the section to form a wall adapted to lead 65 the advance end of the cigarette to the plane

of such edge during endwise movement of the cigarette to remove it from the case, and means overlying and extending transversely to the direction of length of such depressions to retain cigarettes in position, said 70 means being positioned to expose opposite ends of the cigarettes for distances sufficient to permit free manipulation at the rear end of the cigarette to advance the cigarette and project its opposite end beyond such edge. 75

3. In a cigarette case, a dished leaf section having parallel depressions of a length greater than that of the cigarettes and with the advance end of each depression decreasing in depth toward the adjacent edge of 80 the section to form a wall adapted to lead the advance end of the cigarette to the plane of such edge during endwise movement of the cigarette to remove it from the case, and a band overlying intermediate portions 85 of the cigarettes and having depressions complementary to such section depressions to form pocket-like configurations through which the cigarettes extend, said band being positioned to expose the rear end of each 90 cigarette for a distance sufficient to permit free manipulation at such end to advance the cigarette to project the opposite end beyond such edge.

4. In a cigarette case, a dished leaf section 95 having parallel depressions of a length greater than that of the cigarettes and with the advance end of each depression decreasing in depth toward the adjacent edge of the section to form a wall adapted to lead 100 the advance end of the cigarette to the plane of such edge during endwise movement of the cigarette to remove it from the case, and a band overlying intermediate portions 105 of the cigarettes and having depressions complementary to such section depressions to form pocket-like configurations through which the cigarettes extend, said band being positioned to expose the rear end of each cigarette for a distance sufficient to 110 permit free manipulation at such end to advance the cigarette to project the opposite end beyond such edge, said band being supported solely at its ends.

5. A cigarette case comprising a pair of 115 hingedly connected leaf sections oppositely dished to inclose the cigarettes when the sections are closed, at least one of said sections being corrugated to form depressions of a length greater than the length of the 120 cigarettes and within which the cigarettes are seated individually, said depressions each having an end portion decreasing in depth toward a section edge, and a band extending transversely of the depressions 125 and normally overlying the contained cigarettes intermediate the cigarette ends to retain the cigarettes in such depressions while permitting endwise movement thereof, the position of the band exposing a length of 130

5 cigarette sufficient to permit free manipulation at the rear end of the cigarette to carry the opposite end of such cigarette beyond the section edge, the configuration of the depression end leading the advance end of a cigarette to a completely-exposed position during such advancing movement.

6. A cigarette case comprising a pair of hingedly connected leaf sections oppositely 10 dished to inclose the cigarettes when the sections are closed, at least one of said sections being corrugated to form depressions of a length greater than the length of the cigarettes and within which the cigarettes are 15 seated individually, and a band extending transversely of the direction of length of the depressions intermediate of and spaced from the depression ends, said band being corrugated oppositely to said depressions and co-operating therewith to complete pocket-like configurations through which the cigarettes extend, said band normally maintaining the cigarettes seated in such depressions while 20 permitting endwise movement of a cigarette in the direction of length of its depression at will, the position of the band permitting such movement for a distance sufficient to project the opposite end of the cigarette beyond the section edge.

7. A cigarette case comprising a pair of hingedly connected leaf sections oppositely 25 dished to inclose the cigarettes when the sections are closed, at least one of said sections being corrugated to form depressions of a length greater than the length of the cigarettes and within which the cigarettes are 30 seated individually, and a band extending transversely of the direction of length of the depressions intermediate of and spaced from the depression ends, said band being corrugated oppositely to said depressions and co-operating therewith to complete pocket-like configurations through which the cigarettes extend, said band normally maintaining the cigarettes seated in such depressions while permitting endwise movement of a cigarette 35 in the direction of length of its depression at will, the position of the band permitting such movement for a distance sufficient to project the opposite end of the cigarette beyond the section edge, said band being mov- 40 ably supported, movements of said band permitting complete exposure of the depressions.

8. A cigarette case comprising a pair of hingedly connected leaf sections oppositely 45 dished to inclose the cigarettes when the sections are closed, at least one of said sections being corrugated to form depressions of a length greater than the length of the cigarettes and within which the cigarettes are 50 seated individually, each depression having its end portions curved toward the section edge to gradually decrease the depth of the depressions at such end portions, such curved portions being of a length to place the cigarette ends thereon when the cigarette is in 55 position, and a band extending transversely to the direction of length of the depressions and adapted to overlie the depression ends, said band normally maintaining the cigarettes in the depressions while permitting endwise movement thereof, the position of the band and of the curved portions of the depressions permitting such endwise movement by manipulation at the rear end of a cigarette to freely deliver the advance end of the cigarette beyond a section edge and retain the cigarette body against damage under the shifting delivery movements.

9. A cigarette case comprising a pair of hingedly connected leaf sections oppositely 60 dished to inclose the cigarettes when the sections are closed, at least one of said sections being corrugated to form depressions of a length greater than the length of the cigarettes and within which the cigarettes are

seated individually, and a band movably supported at its ends and extending transversely of the direction of length of the depression intermediate of and spaced from the depression ends, said band being corrugated oppositely to said depressions and co-operating therewith to complete pocket-like configurations through which the cigarettes extend, said band normally maintaining the cigarettes seated in such depressions while 70 permitting endwise movement of a cigarette in the direction of length of its depression at will, the position of the band permitting such movement for a distance sufficient to project the opposite end of the cigarette beyond the section edge.

10. A cigarette case comprising a pair of hingedly connected leaf sections oppositely 75 dished to inclose the cigarettes when the sections are closed, said sections being oppositely corrugated to combinedly produce opposing depressions for housing the cigarettes when the latter are individually positioned, and a band extending transversely to the direction of length of the depressions and 80 supported at its ends at opposite edges of one of said sections and adapted to retain the cigarettes in position within the depressions of such section, said band being positioned intermediate of and spaced from the depression ends and corrugated in correspondence with and adapted to nest within the opposite leaf section, said band overlying the contained cigarettes when the case is 85 open.

11. A cigarette case comprising a pair of hingedly-connected leaf sections oppositely 90 dished to inclose the cigarettes when the sections are closed, and a band extending transversely of the direction of length 95 of the cigarettes and located intermediate of and spaced from the ends of the cigarettes, said band being corrugated to form parallel concavities facing a leaf section wall and adapted to coöperate with said wall in forming pockets to receive the cigarettes, said band normally maintaining the cigarettes individually seated while permitting endwise movement of a cigarette in the direction of cigarette length at will, the 100 position of the band permitting such movement for a distance sufficient to project the opposite end of the cigarette beyond the section edge.

12. A cigarette case comprising a pair of hingedly-connected leaf sections oppositely 105 dished to inclose the cigarettes when the sections are closed, and a band extending transversely of the direction of length of the cigarettes and located intermediate of and 110 spaced from the ends of the cigarettes, said band being corrugated to form parallel concavities facing a leaf section wall and adapted to coöperate with said wall in forming pockets to receive the cigarettes, said band 115

normally maintaining the cigarettes individually seated while permitting endwise movement of a cigarette in the direction of cigarette length at will, the position of the 5 band permitting such movement for a distance sufficient to project the opposite end of the cigarette beyond the section edge, said band being swingingly supported to move toward and from cigarette-holding position.

12. A cigarette case comprising a pair of hinged-connected leaf sections oppositely dished to inclose the cigarettes when the sections are closed, and a band extending transversely of the direction of length of the cigarettes and located intermediate of and spaced from the ends of the cigarettes, said band being corrugated to form parallel concavities facing a leaf section wall and adapted to coöperate with said wall in forming pockets to receive the cigarettes, said band normally maintaining the cigarettes individually seated while permitting endwise movement of a cigarette in the direction of 25 cigarette length at will, the position of the band permitting such movement for a distance sufficient to project the opposite end of the cigarette beyond the section edge, said band being supported to swing on an 30 axis substantially corresponding to the axis of the hinge connection to permit movement of the band toward and from its cigarette-holding position.

13. A cigarette case comprising a pair of 35 hinged-connected leaf sections oppositely dished to inclose the cigarettes when the sections are closed, and a band extending transversely of the direction of length of the cigarettes and located intermediate of and spaced from the ends of the cigarettes, said band being corrugated to form parallel concavities facing a leaf section wall and adapted to coöperate with said wall in forming pockets to receive the cigarettes, said band 40 normally maintaining the cigarettes individually seated while permitting such movement for a distance sufficient to project the opposite end of the cigarette beyond the sec- 45

tion edge, said hinge connection including a pintle, and said band being supported by 50 said pintle to permit swinging movements toward and from cigarette-holding position.

14. A cigarette case comprising a pair of hinged-connected leaf sections oppositely dished to inclose the cigarettes when the sections are closed, and a band extending transversely of the direction of length of the cigarettes and located intermediate of and spaced from the ends of the cigarettes, said band being corrugated to form parallel concavities facing a leaf section wall and adapted to coöperate with said wall in forming pockets to receive the cigarettes, said band normally maintaining the cigarettes individually seated while permitting endwise movement of a cigarette in the direction of cigarette length at will, the position of the band permitting such movement for a distance sufficient to project the opposite end of the cigarette beyond the section edge, said hinge 70 connection including a pintle having its ends extending laterally of the direction of pintle length, said band being carried by said laterally-extending portions of the pintle, whereby the band may be swung toward and 75 from cigarette-holding position.

15. A cigarette case comprising a pair of hinged-connected leaf sections oppositely dished to inclose the cigarettes when the sections are closed, and a band extending transversely of the direction of length of the cigarettes and located intermediate of and spaced from the ends of the cigarettes, said band having parallel concavities arranged successively in the direction of length of the 80 band, the direction of length of the concavities extending transverse to the direction of length of the band, said concavities facing a leaf section wall and coöperating therewith in forming pockets in which the cigarettes 85 are individually seated, said band being movable to expose the entire length of the cigarettes.

In testimony whereof I affix my signature.

SADIE L. JOHNSTON.
